ARTIFICIAL BRICK CORNER CONSTRUCTION

Robert R. Brenner, Milwaukee, Wis., assignor to
Eve Brenner and Rac Kaiser, both of Milwaukee, Wis.

Application August 9, 1938, Serial No. 223,929

4 Claims. (Cl. 20—5)

This invention relates to brick simulating, corner forming, structural elements and to the method of making them.

It has become a practice to apply new siding to existing buildings. Such siding may consist of asphalt sheet material in strip form. One difficulty encountered in the use of such material has been its tendency to crack at joints or bends. Such cracks allow moisture to enter the wall structure. Another difficulty is the tendency of the siding to creep or bulge at corners. Such creeping or bulging has been cumulative in some instances so as to seriously mar the appearance of the building. The walls have appeared out of plumb.

One object of this invention is to provide a means which avoids creep. Another object is to provide relatively indestructible means. A further object is to provide a brick simulating corner element which will avoid the deficiencies of previous constructions.

Other and further objects will appear from the following description when taken in connection with the accompanying drawings wherein like numerals represent corresponding parts in the various figures.

Figure 1 is a perspective view of a brick simulating corner construction embodying features of the invention.

Figure 2 is a perspective view of one of the corner elements.

Figure 3 is a vertical sectional view on line 3—3 of Fig. 1 illustrating the manner in which the elements overlap vertically.

Figure 4 is a fragmentary longitudinal sectional view of one of the corner strips constructed in accordance with this invention.

Figure 5 illustrates one form of siding.

Figure 6 shows a piece of siding cut to represent a brick with mortar.

Figure 7 shows a metal plane element.

Figure 8 shows the metal base formed into a dihedral angle for right or left hand brick construction.

Figure 9 illustrates the application of binder to the base plate.

Figure 10 illustrates a completed corner element for an outside corner.

Figure 11 shows the features of the invention adapted to inside corner construction.

Referring more particularly to the drawings, Figure 2 shows one of the corner units 20 comprising a metal base plate 21 bent into a dihedral angle forming the foundation means, with

a surface element 22 partially covering the former and secured thereto by a binder 23.

The plate 21 formed of sheet metal is bent at 24 to form the corner, with a short end 25 and a relatively long portion 26. The coarse brick simulating surface is indicated generally at 27. Adjoining the brick simulating surface is a strip 28 of relatively fine grain gravel simulating mortar in conventional brick construction. The end portions 29 and 30 contain a layer of the finer grain gravel simulating the vertical mortar strip similar to material in strip 28.

The device is formed by heating the pre-shaped metal portion 21 and applying a binder 23. A sheet of artificial brick composition material is heated enough to bend without cracking and is then applied to the binder. The assembly is then placed in a jig and pressed firmly together to form a unitary element. Hot gravel is then applied to the ends 29 and 30.

The completed unit has an outer brick space 27 bordered by a horizontal strip 28 as mortar, both secured to the metal base, which latter extends on three sides of the brick forming a recessed marginal portion 31.

According to a preferred method of this invention the asphalt sheets 32, simulating brick 33 and mortar 34, are nailed in overlapping relation on the side of a house or other building and when completed simulate brick with mortar joints 30 therebetween. This siding is very desirable and effective because of its aesthetic appeal, and its effectiveness as an insulator and weatherproof surface. The preformed corner construction is nailed to the building in the same way as the asphalt sheets and requires no special skill in installation.

The method of making the corner elements is more clearly explained by reference to Figs. 5 to 11. The siding strip 32 of Fig. 5 may be cut to form brick elements 27 as in Fig. 6 with the horizontal strip 28. The strip 28 is of fine grain material and may be black, brown, white or other color simulating an appropriate type of mortar. This strip is cut to desired size, one satisfactory size being 8 inches by 3 inches with the mortar strip $\frac{1}{2}$ inch wide. These strips are then washed on the reverse side with gasoline to remove the powder substance or other foreign matter.

The base plate 21 in Fig. 7 is heated and formed as in Fig. 8. The plate 35 corresponds to the right hand brick as in Fig. 1 and 36 indicates a base for the left hand brick. The plates are bent as at 24 and 37 for outside corners. The outer surface of the plate is coated with a hot

asphaltic composition 23, in Fig. 9, although other binders may be used. One example of a satisfactory binder is 40% lapp cement and 60% asphalt. Other binders without lapp cement have 5 also been used. The binder coats a large part of the exposed surface of the plate but not all of it as in Fig. 9.

This binder may be applied manually by a brush and is generally a hot asphalt composition.

10 The metal base is then placed in a jig and the brick of Fig. 6 is heated and applied to the base. This may be done by hand. The jig is then operated to completely wedge the base and brick together. The device is removed from the jig and 15 heated granular materials are applied to the exposed coated ends 38 and 39 of Fig. 9 as in Fig. 10. This provides mortar lines for the ends of the brick. These granules may now be tamped by a hammer or the like into the asphalt base.

20 Where interstices or cracks form in the corner non-heated brick granules are applied to fill them up. These are tamped to leave a uniform outer surface.

In Fig. 11 the inside type corner is shown. 25 Here the cracks, if any, would be inside but even so their presence should be corrected. Here again the plate 40 has the brick surface 41 and mortar line 42, with the recessed margin 43.

In Fig. 1 the device is assembled with several 30 siding strips and other corner units to form a wall construction. The recessed marginal border 31 is placed upwardly. Each unit overlaps a lower unit. Adjacent siding also overlaps the ends 30 and 31 as seen in Fig. 4.

35 This application is a continuation in part for my copending application Serial Number 134,009, filed March 31, 1937.

Although a preferred embodiment of this invention and method of making it are shown and 40 described, variation within the true spirit and scope of the same are to be determined by the appended claims.

What I claim is:

1. A new article of manufacture as a corner 45 strip for simulating brick wall corner constructions comprising a metallic plane element formed into a dihedral angle, a surface element largely covering the outer surface of said metal element and leaving a free marginal area of the metal

element exposed, said surface element having its major portion covered by a coarse grain material and the upper marginal edge thereof covered by a fine grain material, and means interposed between said elements and binding them together, 5 said means partially covering the exposed marginal area of said metal element including the ends of the latter and in said marginal areas being covered by a fine grain material.

2. A new article of manufacture as a corner 10 strip for simulating brick wall constructions comprising a metal plane element, a surface element partially covering the surface of said metal element and leaving a free marginal area along the end walls thereof exposed, said surface element 15 partially covered by a coarse grain material, means interposed between said elements forming a binder therebetween, said latter means covering the exposed marginal area of said metal element, and a fine grain material covering the 20 latter portion of said binding means and the remaining portions of said surface element.

3. A corner strip for simulating brick wall corner construction including a rigid base element 25 for engagement with a wall, a surface element superimposed on the base element, the ends of the surface element falling short of the ends of the base element, a binder interposed between the base and surface elements and spread over the 30 ends of the base element, beyond the surface element terminals, and a grain material covering the binder beyond said surface element terminals.

4. A new article of manufacture consisting of a corner strip for simulating brick wall corner construction including a plane element of a contour 35 conforming to the shape of the corner, a surface element substantially covering the outer surface of said plane element, the major portion of the surface element being covered by a coarse grain material and a marginal edge thereof being 40 covered by a fine grain material, means interposed between said plane element and surface element for binding them together, said means also extending over the uncovered portion of the plane element, and a granular material covering 45 said means and being held from displacement by the latter.

ROBERT R. BRENNER.
